CLOTHESLINE SUPPORT

Ezekiel Coss, Brooklyn, N. Y.

Application April 4, 1950, Serial No. 153,845

3 Claims. (Cl. 211--119.06)

1

This invention relates to clothesline supports and especially to that type of support adapted to be fastened to a window frame of a building and on which an endless clothesline is supported, the other end of the clothesline being supported by a pulley attached to a pole or other support located at a distance from the present clothesline support.

It is a common practice to attach a pulley to a window frame and another pulley to a distant support and to run an endless clothesline about these pulleys so that clothing and other articles may be fastened to the line and drawn out for drying and subsequently drawn in and removed from the line. Such an arrangement requires the user to lean from the window and pull horizontally toward the body when manipulating the line, which is awkward, inconvenient and dangerous, owing to the liability of losing one's balance.

It is an object of the present invention to provide a clothesline support adapted to be attached to a window frame and which may be pivoted from a vertical position outside the window frame when not in use to a horizontal position bringing a portion of the clothesline within the room for attaching clothes thereto, and hence avoiding the necessity of leaning out of the window in order to operate the line.

It is a further object of the invention to provide a clothesline support of the type set forth above, in which a pivotal mounting means is provided which will allow the device to swing on its pivot and thus compensate for a deflection of the clothesline due to a high wind, thereby to avoid damage to the device or to the clothesline.

A further object of the invention is to provide a simple and durable construction for the purposes above stated, so as to reduce the cost thereof and provide a practical device for these purposes.

A further object of the invention is to provide a device of this type which can be readily and quickly fixed to a window frame and when not in use be easily removed therefrom.

The invention will be more fully understood by reference to the accompanying drawing in which similar reference characters denote corresponding parts and in which:

Figure 1 is a side elevation of the device, the same being shown as attached to a window frame, portions of the window sash being shown in section, the device being shown in its operative position extending horizontally inwardly through the window frame.

Figure 2 is a top plan view of the device taken

2

on the line 2--2 of Figure 1, showing the same attached to a window frame, portions of the window frame and wall structure being shown in section, the device being shown in its operative position extending horizontally inwardly through the window frame.

Figure 3 is an end elevation of the device as viewed from the left hand end of Figure 1, the top and bottom reaches of the clothesline being shown in section.

Figure 4 is a section on the line 4--4 of Figure 1.

Figure 5 is a section on the line 5--5 of Figure 1.

15 Figure 6 is a section on the line 6--6 of Figure 1.

Figure 7 is a side elevation of the device, the same being shown in its non-operative folded position, in which it is disposed vertically alongside the window frame and the outer wall of the building.

In the drawing, the numeral 10 designates the outer wall of a building. A portion of a window frame is shown at 11 and the window frame includes the usual guide members 12 which serve to guide the window sashes 13.

A bracket member 15 is provided for attaching the device to the outer side of a window frame, and includes tubular portions 17 adapted to receive a removable pivot pin 18. The bracket member 15 is formed with apertures to receive screws 19 for the purpose of attaching the bracket member 15 to the portion 11 of the window frame. A plate member 16 arranged in end to end relation with respect to the bracket member 15 and is connected to the bracket member for swinging movement toward and away from the latter by means of tubular portions 17 which are pivotally mounted on the pivot pin 18. A second plate member 21 is arranged in face to face relation with respect to the plate member 16 and is connected intermediate its ends to the first plate member 16 for rotary movement about an axis transverse of the plate member 16 or pin 20 which projects transversely from the plate member 16 and on which the plate member 21 is rotatably mounted. A guide pulley 60 is positioned in side by side relation with respect to the second plate member 21 and is mounted on the aforesaid axis of pin 20 for rotation therearound.

A hollow tubular arm 22 is arranged in end to end spaced relation with respect to the guide pulley 60 and has one end fixedly secured to the second plate member 21, by means of a bracket 23. The arm 22 is secured to the bracket 23 by

means of rivets 24 and the bracket 23 is secured to the plate member 21 by means of rivets 25.

The arm 22 is of a length sufficient to extend from a position outside of the window frame to a point well within said frame, as shown in Figures 1 and 2, and has mounted on its other end a bracket member 26 secured to the arm 22 by rivets 27. The bracket member 26 is formed by bending a piece of sheet metal upon itself to form a U-shaped member having parallel spaced side portions 26a. A clothesline supporting pulley 28 is mounted on a shaft 29 carried by the bracket member 26.

A pair of pins 30 is secured in the portions 26a of the bracket member 26, and serves to support a plate member 32. The plate member 32 is spaced from and centered with respect to the members 26a by means of spacer members 31. The plate member 32 is provided with a slot 33 which includes a flared entrance portion 34 disposed generally parallel to the arm 22, and a portion 35 disposed at right angles thereto.

The plate member 21 is provided with an extension 36 having a slot 37 formed therein. Slot 37 includes a flared entrance portion 38 disposed parallel to the arm 22, and a portion 39 disposed at right angles thereto.

Plate 21 also has formed therein a pair of slots 40 and 41. Slots 40 and 41 extend inwardly from the semi-circular edge 42 of the plate 21. The semi-circular edge 42 is formed about the pin 20 as a center.

A latch member 43 is pivotally mounted on a pivot pin 44 carried by the plate member 16. Latch member 43 is provided with a pin 45 adapted to be seated in either of the slots 40 or 41, to hold the arm 22 in either the horizontal operative position thereof or the vertical non-operative position thereof, respectively. A projection 46 is provided on the latch member 43 to serve as a handle therefor. A lug 51 is formed on the latch member 43 and serves as a stop means for limiting the outward pivotal movement thereof.

A guide member 47 is mounted for sliding movement on the arm 22. The guide member 47 is formed by bending a strip of sheet metal upon itself to form a sleeve portion 48 and parallel leg portions 49. The leg portions 49 are secured together by rivets 56. A bolt 51 provided with a wing nut 52 is disposed in slots 53 formed in the leg portions 49. At the lower ends thereof the leg portions 49 are spaced apart as shown at 56 to accommodate a clothesline guide roller 54 mounted on a shaft 55 carried by the leg portions 49. The bolt 51 is adapted to be engaged in either of the slots 33 or 37, and provides means for securing the guide member 47 to either of the members 32 or 36.

A clothesline 57 is adapted to be passed over the guide pulley 50, through the tubular arm 22, around the clothesline supporting pulley 28, and then over the guide roller 54. The other end of the clothesline is supported by a pulley, not shown, mounted on a post or other support located at a distance from the present clothesline support. Figure 7 shows the position of the device when not in use.

To use the device, the latch member 43 is raised, thus moving the pin 45 out of the slot 41. The arm 22 is then raised to a horizontal position and the latch member 43 is moved down to a position wherein the pin 45 engages the slot 40. This latches the arm 22 in the horizontal position wherein the arm 22 and the clothesline 57 are extended through the window frame and

into the room. The guide member 47 is then disengaged from the part 36 by loosening the wing nut 52 and sliding the bolt 51 out of the slot 37. To do this, the bolt 51 must first be raised vertically and then moved horizontally. The guide member 47 is then slid along the arm 22 until it abuts the bracket member 26. It is then secured to the plate member 32 by engaging the bolt 51 within the slot 33. In this position, the roller 54 and the arms 50 serve as a guide means for the clothesline 57, but do not interfere with the hanging of clothes on the lower reach of the clothesline 57. It is then an easy matter to attach clothes to the lower reach of the clothesline 57 and move the clothes outwardly by pulling on the clothesline.

Since the device is pivoted on the pin 18, it will swing in a horizontal plane to compensate for deflection of the clothesline due to a high wind or for other reasons, and thus prevent damage to the device or to the clothesline. Also, the pivot 18 causes the device to automatically align itself with the pulley at the far end of the clothesline.

When the clothes have been removed from the line, the device may be moved to the position shown in Figure 7, so that it will be out of the way. To do this, the guide member 47 is first released from the member 32 and slid along the arm 22 until it abuts the bracket 23. In this position it is secured to the part 38 by engaging the bolt 51 in the slot 37. This positions the guide roller 54 so that it will properly guide and support the lower reach of the clothesline 57 and maintain it taut when the device is swung to the position shown in Figure 7. To swing the device to this position, it is merely necessary to raise the latch means 43 to disengage the pin 45 from the slot 40, pivot the arm 22 downwardly to a vertical position, and then re-engage the latch means 43 so that the pin 45 is engaged in the slot 41. This locks the arm 22 in its vertical non-operative position. If desired, the device can be quickly detached from the window frame merely by removing the pivot pin 18.

While I have herein shown and described a preferred form of my invention, it is to be understood that changes may be made in the form, proportion and construction of the several parts without departing from the spirit of my invention, and within the scope of the appended claims.

I claim:

1. A clothesline support comprising a bracket member adapted to be attached to a side of a window frame, a first plate member arranged in end to end relation with respect to said bracket member and connected to the latter member for swinging movement toward and away from the latter, a second plate member arranged in face to face relation with respect to said first plate member and connected intermediate its ends to said first plate member for rotary movement about an axis transverse of the latter, a guide pulley positioned in side by side relation with respect to said second plate member and mounted on said axis for rotation therearound, a hollow arm arranged in end to end spaced relation with respect to said guide pulley and having one end fixedly secured to said second plate member, a second bracket member arranged longitudinally of said arm adjacent the other end of the latter and fixedly secured to the other end of said arm, a pulley arranged longitudinally of said arm adjacent the other end thereof and connected to

said bracket member adjacent one end thereof for rotation about a second axis transverse of said bracket member for supporting a clothesline, a guide member positioned on said arm intermediate said second plate member and said second bracket member and mounted on said arm for sliding movement into and out of engagement with said plate member and said second bracket member, a third plate member arranged longitudinally and inwardly of the other end of said second bracket member and fixedly secured to the other end of said second bracket member, an extension arranged longitudinally of and inwardly of said second plate member and carried by the latter, and a securing element arranged transversely of and extending through said guide member and engageable with means formed on said third plate member when said guide member is in engagement with said third plate member and with means formed on said extension when said guide member is in engagement with said extension.

2. A clothesline support comprising a bracket member adapted to be attached to a side of a window frame, a first plate member arranged in end to end relation with respect to said bracket member and connected to the latter member for swinging movement toward and away from the latter, a second plate member arranged in face to face relation with respect to said first plate member and connected intermediate its ends to said first plate member for rotary movement about an axis transverse of the latter, a guide pulley positioned in side by side relation with respect to said second plate member and mounted on said axis for rotation therearound, a hollow arm arranged in end to end spaced relation with respect to said guide pulley and having one end fixedly secured to said second plate member, a second bracket member arranged longitudinally of said arm adjacent the other end thereof and connected to said second bracket member adjacent one end thereof for rotation about a second axis transverse of said second bracket member for supporting a clothesline, a guide member positioned on said arm intermediate said second plate member and said second bracket member and mounted on said arm for slidable movement into and out of engagement with said second plate member and said second bracket member, a third plate member arranged longitudinally and inwardly of the other end of said second bracket member and fixedly secured to the other end of said second bracket member, an extension arranged longitudinally of and inwardly of said second plate member and carried by the latter, a securing element arranged transversely of and extending through said guide member and engageable with means formed on said third plate member when said guide member is in engagement with said third plate member and with

means formed on said extension when said guide member is in engagement with said extension, and a latch member pivotally carried by said first plate member and selectively seatable in spaced receiving means formed in said second plate member upon rotary movement of the latter member.

3. A clothesline support comprising a bracket member adapted to be attached to a side of a window frame, a first plate member arranged in end to end relation with respect to said bracket member and connected to the latter member for swinging movement toward and away from the latter, a second plate member arranged in face to face relation with respect to said first plate member and connected intermediate its ends to said first plate member for rotary movement about an axis transverse of the latter, a guide pulley positioned in side by side relation with respect to said second plate member and mounted on said axis for rotation therearound, a hollow arm arranged in end to end spaced relation with respect to said guide pulley having one end fixedly secured to said second plate member, a second bracket member arranged longitudinally of said arm adjacent the other end thereof and connected to said second bracket member adjacent one end thereof for rotation about a second axis transverse of said second bracket member for supporting a clothesline, a guide member positioned on said arm intermediate said second plate member and said second bracket member and mounted on said arm for sliding movement into and out of engagement with said second plate member and said second bracket member, a third plate member arranged longitudinally and inwardly of the other end of said second bracket member and fixedly secured to the other end of said second bracket member, an extension arranged longitudinally of and inwardly of said second plate member and carried by the latter, said extension facing said third plate member, and a securing element arranged transversely of and extending through said guide member and engageable with a slot formed on said third plate member when said guide member is in engagement with said third plate member and with a slot formed on said extension when said guide member is in engagement with said extension.
